UNITED STATES PATENT OFFICE.

BAYARD E. TAYLOR, OF OAK PARK, ILLINOIS.

LATCH FOR AUTOMOBILE DOORS.

1,425,552.

Specification of Letters Patent. Patented Aug. 15, 1922.

Application filed June 21, 1920. Serial No. 390,343.

To all whom it may concern:

Be it known that I, BAYARD E. TAYLOR, a citizen of the United States, and a resident of the village of Oak Park, in the county of Cook and State of Illinois, have invented 5 certain new and useful Improvements in a Latch for Automobile Doors; and I do hereby declare that the following is a full, clear, and exact description of the same, reference 10 being had to the accompanying drawings, and to the numerals of reference marked thereon, which form a part of this specification.

This invention relates to an improved type 15 of a latching mechanism for an automobile door, and more particularly to a lock wherein a normally projected spring controlled latching bolt is adapted to be retracted by the operation of an outer handle or by means 20 of a rotatable inner handle which, when operated, acts through a cam mechanism to slidably adjust a vertical shaft to cause retraction of the latching bolt from its projected latching position to permit opening 25 of the door.

It is an object of this invention to provide a vehicle door lock having a vertically disposed slidable shaft for releasing the lock latch.

30 A further object of the invention is the construction of a vehicle door latch wherein the latching members are adapted to be released from the inner side of the door by rotating a handle to cause operation of the 35 latching members by a vertically adjustable shaft.

Another object of the invention is to provide an automobile door lock with a pivoted member adapted to be actuated, to cause release of a latching member, by pulling or pushing a vertical shaft operable by a rotatable handle.

40 It is furthermore an object of the invention to provide a vehicle door lock with a latch releasing mechanism operable from the interior of a closed vehicle body by rotating a handle.

50 It is an important object of this invention to provide a vehicle door lock wherein a latch is adapted to be retracted from the interior of a closed vehicle body by rotating a handle to cause a cam mechanism to slidably shift a vertical rod.

Other and further important objects of this invention will be apparent from the disclosures in the specification and drawings. 55

The invention (in a preferred form) is illustrated in the drawings and hereinafter more fully described.

On the drawings:

60 Figure 1 is a front elevation of a door lock embodying the principles of this invention and showing one of the lock operating handles.

Figure 2 is an enlarged view of the lock 65 with the casing removed and showing parts in section.

Figure 3 is an end view thereof with the casing in place and with part of the upper handle omitted.

70 Figure 4 is a fragmentary detail section taken on line 4—4 of Figure 2.

Figure 5 is a rear view of the wedge member.

75 Figure 6 is a front elevation of the back plate partly in section and showing the latch bolt in position.

Figure 7 is a fragmentary detail section taken on line 7—7 of Figure 2.

80 Figure 8 is a horizontal transverse section taken through the door lock, the door and the door frame.

Figure 9 is an end view of the door lock looking at the flanged end of the back plate.

85 Figure 10 is an enlarged view of the strike plate showing part of the door jamb.

Figure 11 is a fragmentary detail section taken on line 11—11 of Figure 2.

90 Figure 12 is a fragmentary vertical detail section taken through the upper portion of the inner door handle.

Figure 13 is a top plan view of the upper handle bearing cap showing the cam forming a part thereof.

95 Figure 14 is a bottom plan view of the cam end of the upper handle.

Figure 15 is a front elevation of a modified form of door lock with the casing removed.

100 Figure 16 is a top plan view of the upper handle mechanism.

Figure 17 is a sectional view taken on line 17—17 of Figure 16 showing parts in elevation.

105 Figure 18 is a fragmentary detail section taken on line 18—18 of Figure 17.

Figure 19 is a sectional bottom plan view of the upper handle showing the cam and taken on line 19—19 of Figure 17.

Figure 20 is a detail section taken on line 5 20—20 of Figure 17 with parts omitted.

As shown on the drawings:

The reference numeral 1 indicates an automobile body door frame or jamb provided with a latch receiving recess 2 and having 10 secured on the jamb face thereof a strike plate 3. Integrally formed on the strike plate is an abutment 4 provided with an inclined surface 5 which affords an increased bearing surface for a wedge hereinafter 15 described. Hingedly mounted in the door frame 1 is a door 6 having mounted in a shallow recess thereof a comparatively thin door lock embodying the principles of this invention. The door lock illustrated in Figures 1 to 14 inclusive, embraces a mounting 20 plate or back plate 7, one end of which is bent forwardly at an angle to afford a flange 8 having an opening therein to permit the lock latching members to project there- 25 through. A T-bar 8^a is secured on the outer edge of the door.

Secured between two lugs 9 struck from the back plate 7 is the inner end of a coiled controlling spring 10, the outer end of 30 which projects downwardly and engages against a pivoted lever or arm 11. The upper end of the lever 11 is pivoted on a pin 12 integrally formed on one side of the inner end of a slidable wedge bar 13. Integrally formed on the opposite side of the 35 slidable bar 13 is a guide block or lug 14, which projects into a horizontal guide slot 15 formed in a cover or casing plate 16 to enclose the operating mechanisms of the 40 lock. The rearward movement of the wedge bar 13 is limited by the lug 14 striking the casing at the end of the guide slot 15. The wedge bar 13 has rigidly secured on the end thereof a wedge block 17, which is slidable 45 through the opening in the flange 8 and is furthermore adapted by rearward movement of the wedge bar 13 to move in a recess 18 cut in the door 6 as shown in Figure 8. The casing 16 is provided with an opening 50 19 to permit retraction of the wedge 17.

The wedge slide bar 13 is cut away at the sides thereof to afford shoulders 20 adapted to contact the inner ends of flanges 21 integrally formed on opposite margins of a 55 slidable latch bolt 22. Integrally formed on the inner end of the latch bolt 22 is a downwardly directed arm 23, the lower end of which is deflected and bent inwardly toward the back plate 7 to form a lug or flange 24. Also integrally formed on the 60 latch bolt arm 23 is a horizontal guide member or arm 25, which is deflected to permit the same to slidably engage in a longitudinal guide slot 26 provided in the casing 16. 65 The end of the arm 25 is bent toward the

back plate 7 to form a lug or flange 27. As shown in Figure 2, the lower end of the lever 11 contacts the flange 24 of the latch bolt arm 23 to permit the spring 10 to hold the latch bolt in projected position. To re- 70 tract the latch bolt 22 to permit opening of the door from the exterior of a vehicle, an outer door handle or thumb button 28 is provided having a squared stem 29, the inner end of which projects into a square 75 opening formed in a rotatable collar 30 journaled between the back plate 7 and the casing 16 as illustrated in Figure 7. Integrally formed on the collar 30 is a dog or roll back 31, the free end of which is in engagement with the latch bolt arm 23. When the thumb button 28 is turned the roll back 31 acts to force the latch bolt 22 inwardly together with the wedge 17 since the flanges 21 of the latch bolt are in contact with the 80 shoulders 20 of the wedge slide bar 13.

For the purpose of opening the door from the interior of a closed vehicle body a second or inner rotatable handle 32 is provided on the top of the door. A head 33 is integrally formed at one end of the handle 32, and integrally formed on the bottom of said head is a cam 34, which normally seats against a stationary cam 35 formed within a sleeve 36 integrally formed on a cap plate 37. The cap plate 37 is secured to the top of the door 6 by screws or other suitable means. Secured to the upper margin of the back plate 7 is an upright bracket 38, the upper end of which is bent forwardly to 90 form a horizontal lug or flange 39 having a threaded aperture therein. Threaded into the flange 29 is the lower threaded end of a sleeve or cylindrical housing 40, the upper end of which is engaged in the lower end 95 of the sleeve 36 below a horizontal partition 41, as illustrated in Figure 12. The head 33 of the handle 32 is secured by means of a screw 42 on the upper cylindrical end of a vertical rod or shaft 43, which projects 100 downwardly through the sleeve 40. The vertical shaft 43 is formed with a square neck 44 near its upper end. The square neck 44 is slidably engaged through a square opening provided in the partition 41. 110 The vertical shaft is thus prevented from being rotated and is only permitted to be slidably adjusted vertically. The lower end of the vertical shaft 43 is threaded and has adjustably mounted thereon a guide block 115 45, which is engaged to slide in a vertical guide channel 46 formed by depressing a portion of the back plate 7. Integrally formed on one side of the block 45 is a horizontal lug or tooth 47, which normally 120 is positioned to engage beneath the short arm 48 of a bell-crank having a long arm 49. The bell crank is pivotally mounted on a pin 50 provided on the front surface of the 125 back plate 7. The lower end of the long bell 130

downwardly into normal position thereby returning the handle 32 to normal position.

In the preferred form of door lock illustrated in Figures 15 to 20 inclusive, the 5 operation of opening the door from the exterior of the vehicle is identical with the operation hereinbefore described.

For the purpose of opening the door from the interior of the vehicle the handle 51 is 10 rotated in a horizontal plane whereby the handle cam 53 co-acting with the cam 54 serves to slidably force the cam sleeve 55 downwardly. The sleeve 55 thus causes the tubular vertical shaft 61 to slide downwardly thereby pushing the lug 65 against the short bell crank arm 66 and swinging the long bell crank arm 67 rearwardly against the lug 27 to retract the latch bolt 22 and the wedge 17. The swinging of the 15 handle 51 to retract the latching members is such that the door is swung into open position at the same operation. Upon release of the handle 51 the control spring 10 acts through the pivoted arm 11 and the flanged 20 latch bolt arm 25 to pull the long bell crank arm 67 forwardly thereby causing the short bell crank arm 66 to push upwardly on the lug 65 to slide the tubular shaft 61 back into normal position. The upward movement of 25 the shaft 61 causes the cams 54 and 53 to 30 coact to swing the handle 51 back into its normal position.

The various parts of the door lock are 35 preferably punched out of sheet metal thereby obviating machining which would be required in case the parts were cast. Particular attention is directed to the compact arrangement of the thin stamped metal parts which permit a very thin door lock to be 40 constructed.

The novel arrangement of the inner handle mechanisms disclosed in Figures 12 and 17 permits the use of a rotatable inner handle which, when operated, acts through 45 co-acting cam members to pull or push a vertical non-rotatable shaft to cause operation of a pivoted bell crank which in turn acts to retract the lock latching members to permit opening of a vehicle door.

50 Attention is called to the novel construction of the inner handle mechanisms in both forms of the device illustrated by Figures 2 and 17. The longitudinally movable shafts 43 and 61 when installed are adapted to be 55 adjusted with respect to the cam members to maintain a close adjustment of the co-acting parts. In the form of the device illustrated by Figures 2 and 12, the sleeve 40 is first threaded through the bracket flange 39 so 60 that the upper end of the sleeve will engage against the flange 41 when the cap 37 is in place. Before mounting the cap 37 in place, however, the shaft 43 is threaded through the 65 slidable block 45 until the lug 47 thereof engages beneath the short bell-crank arm

48 in its normal position. The cap 37 is next secured in place with the squared neck 44 of the shaft 43 projecting through the squared opening in the partition 41. The shaft 43 when installed is set so that the 70 upper cylindrical end thereof will project upwardly through the cap a distance sufficient to permit the handle cam 34 to seat on the stationary cam 35 when the retaining screw 42 is threaded into the upper end of 75 the shaft 43. It will thus be seen that in the installation of the lock device the longitudinally adjustable shaft 43 may be set to maintain a close adjustment of said shaft with the cam members to insure proper actuation of 80 the latching members when the handle 32 is rotatably operated. Movement of the cam 34 upon the stationary cam 35 acts to slightly elevate the handle 32 as it is rotated.

In the preferred form of the device 85 illustrated in Figure 17, the longitudinally movable shaft 61 is also adapted to be installed to insure a close adjustment of the shaft and its cam 54 with respect to the handle cam 53. In this case the handle 51 90 is adapted to be rotated without elevating the same, since the shaft cam 54 is mounted to slide with the shaft 61 to cause operation of the lock mechanisms.

I am aware that numerous details of 95 construction may be varied through a wide range without departing from the principles of this invention, and I therefore do not purpose limiting the patent granted otherwise than necessitated by the prior art. 100

I claim as my invention:

1. A vehicle door lock comprising a latching member, a wedge member adapted to be moved differentially with respect to said latching member, an arm pivoted on 105 said wedge member and in contact with said latching member, a spring engaged with said arm to cause the same to hold the latching member and said wedge member in projected latching position, pivoted means in 110 engagement with said latching member, a vertically slideable member in contact with said pivoted means, and a mechanism connected to cause vertical adjustment of said slideable member whereby the pivoted means 115 is operated to cause retraction of the latching member and said wedge member.

2. In a vehicle door lock of the class described, relatively movable latch and wedge members, a member pivoted on the 120 wedge member and engaging the latch member, resilient means engaged with said pivoted member to hold the latch and wedge members in projected latching position, pivoted means in engagement with 125 said latch member, and a slideable member for operating said pivoted means to cause retraction of said latch and wedge members.

3. The combination with a lock strike 130

crank arm 49 projects between the back plate 7 and the latch bolt arm 25 and is in contact with the flange 27 of the arm 25.

In the preferred form of door lock illustrated in Figures 15 to 20 inclusive the construction of the lock is substantially the same as that already described with the exception of the inner handle mechanism which is constructed as follows:

10 To open the door 6 from the interior of a closed vehicle body an inner rotatable handle 51 is provided on the top of the door 6. A head 52 is integrally formed at one end of the handle 51 and has integrally formed on the bottom thereof a cam 53. The cam 53 normally seats against a cam 54 formed on the upper end of a slidably sleeve 55. The sleeve 55 is slidably engaged in the sleeve 56 of a cap or plate 20 57 which is rigidly secured by screws or other suitable means on the top of the door 6. A key 58 is secured in the sleeve 56 to permit sliding movement of the sleeve 55 but holding said sleeve from being rotated.

25 A Z-brace 59 is rigidly secured on the cap 57 and has the upper arm thereof engaged on top of the head 52 of the handle 51 to hold the head seated upon a conical boss 60 forming a part of the cap 57. Threaded 30 into the lower end of the slidable cam sleeve 55 is the upper end of a tubular vertical shaft 61, which projects downwardly into the door lock casing 16. The lower end of the vertical tubular shaft 61 is threaded and 35 has adjustably mounted thereon a guide block 62, which is engaged to slide in a vertical guide channel 63 formed in the back plate of the door lock. Projecting downwardly through the handle head 52, 40 the cam sleeve 55 and the tubular shaft 61 is a headed bolt 69, the lower threaded end of which is threaded through a stationary lug or flange 64 rigidly formed on the back plate of the lock. Integrally formed on 45 one side of the block 62 is a horizontal lug or tooth 65, which normally is in a position to engage upon a short arm 66 of a bell crank having a long arm 67. The bell crank is pivotally mounted on a pin 68 provided on the front surface of the back plate 7. The lower end of the long bell crank arm 67 projects between the back plate 7 and the latch bolt arm 25 and is in contact with the flange 27 of said arm 25.

50 55 The operation is as follows:

In the form of door lock shown in Figures 1 to 14 inclusive the spring 10 pressing against the pivoted arm 11 acts to hold the latch bolt 22 and the wedge 17 in their projected positions as shown in Figures 2 and 8. With the door 6 in closed position the latch bolt 22 engages in the jamb opening 2, and the wedge block 17, which has a slidable movement relative to the latch bolt, follows the latch bolt and

wedges against the inclined surface 5 of the abutment 4 which forms a part of the strike plate 3. As a result of the foregoing operation, the wedge block clamps the door to the jamb co-acting as it does with the 70 T-bar 8^a secured on the outer edge of the door to permit the flange of the T-bar to bear over the jamb as shown in Figure 8. The latch bolt and wedge block thus serve to hold the door rigidly in place in the 75 door frame to prevent rattling of the door. The wedge block 17 is slidable with respect to the latch bolt 22 and under the impulse of the spring 10 is shot or driven into the space between the flat surface of the latch 80 bolt and the surface 5 of the strike plate abutment 4.

The closed door 6 may be opened from the exterior of the vehicle by turning the outer handle or thumb button 28, thereby 85 causing the roll back 31 to press against the latch bolt arm 23 to force the latch bolt 22 inwardly against the action of the control spring 10. The flanges 21 of the latch bolt being in contact with the wedge bar 90 13, both the latch bolt and the wedge are simultaneously retracted as a unit. The door may now be swung into open position on its hinges. Release of the thumb button 28 permits the stressed spring 10 95 to again force or shoot the latch bolt 22 and the wedge 17 outwardly through the opening in the back plate flange 8.

To open the door 6 from the interior of the vehicle the inner or upper handle 32 100 is rotated thereby causing the handle cam 34 to move upwardly on the stationary cam 35. The upward movement of the handle cam head 33 serves to draw or pull the slidable vertical shaft 43 upwardly. The 105 upward movement of the shaft 43 causes the block 45 to slide upwardly in the guide channel 46 whereby the lug 47 of said block acts to throw or swing the short bell crank arm 48 upwardly and thereby swing 110 the long bell crank arm 49 rearwardly. The long bell crank arm 49 being in contact with the flange 27 of the latch bolt arm 25, said arm 49 acts to slidably retract the latch bolt 22 and the wedge 17 associated therewith. With the turning of the handle 32, said handle is slightly elevated due to the action of the handle cam 34 on the stationary cam 35. The handle 32 is rotated to pull the slidable shaft 43 upwardly to 115 120 retract the latch bolt and wedge to permit the door 6 to be swung outwardly into open position simultaneously with the operation of the handle. The wedge and latch bolt may be simultaneously retracted by either of the handles 28 or 32 independently of each other from opposite sides of the door. Upon release of the handle 32 the spring 10 acts through the arm 11 and the bell crank 48-49 to pull the vertical shaft 43 125 130

plate, of an abutment integrally formed thereon having an inclined striking surface, a lock, a latch therein, a wedge slidably engaged with said latch, and means engaged 5 with said wedge for projecting the wedge and latch from said lock with the wedge contacting the inclined surface of said abutment.

4. The combination with a lock and the 10 strike plate therefor, of a projection formed on said strike plate having an inclined striking surface, a latch bolt adapted to be projected from said lock, and a wedge

member slidable with respect to said latch bolt and having a straight striking surface 15 parallel to said latch bolt adapted to be moved into engagement with the inclined surface of said projection.

In testimony whereof I have hereunto subscribed my name in the presence of two 20 subscribing witnesses.

BAYARD E. TAYLOR.
